LEO J. GRUBMAN, OF BELLE HARBOR, NEW YORK.

SOUND-PRODUCING DEVICE OR VOICE FOR DOLLS AND THE LIKE.

Application filed September 1, 1925. Serial No. 53,779.

This invention relates to sound producing devices or voices for dolls and the like, and broadly considered has for its primary object and purpose to provide a simple, novel and positively operating means for controlling and articulating the emission of sound in simulation of the word "ma-ma" or other characteristic cry appropriate to the particular toy or figure in which the device is incorporated.

Voces of that type having a bellows or other means for expelling air under pressure through a sounding reed and provided with a valve mechanically operated at intervals to interrupt the emission of the sound through an orifice are now well known in the art. While such devices of recent domestic origin have been found highly satisfactory and have been used in enormous quantities by the doll and toy industry, they have heretofore been of such construction that the costs of manufacture were comparatively high. It is one of the prominent objects of my present improvements to provide a sound emission controlling or articulating means for such voice devices whereby manufacturing costs may be appreciably reduced while at the same time the articulating qualities of the voice will in no wise be impaired. To this end, I provide a central guide post for the movable head of the air expelling bellows together with a normally open valve carried by said head and associated with the sound emission orifice in the wall thereof. The post is provided with spaced means which cooperates with the valve and holds the same in a more or less closed position relative to the orifice to thereby interrupt or impede the passage of sound through the emission orifice at spaced intervals in the descent or collapsing movement of the bellows head.

It is another object of my present improvements to provide in a simple and practical embodiment of the invention, magnetic means influencing the valve member to hold the same in a closed position relative to the emission orifice, said valve being so arranged relative to the bellows head that after the valve passes beyond the range of in-

fluence of the magnetic means, it will have a limited gravity movement independent of the bellows head to its open position.

In a specific embodiment of the invention as herein shown, I provide the central guide post for the movable bellows head with vertically spaced magnetized areas which are adapted to successively attract a valve element in the form of a soft iron washer which slides upon said post with the bellows head and hold said washer in closed positions during predetermined intervals of movement of the bellows head whereby the emission of sound produced in the descent or collapse of the bellows head will be properly articulated.

With the above and other objects in view, the invention consists in the improved sound producing device or voice, and in the form, construction and relative arrangement of its several parts as will be hereinafter more fully described, illustrated in the accompanying drawing and subsequently incorporated in the subjoined claims.

In the drawings, wherein I have illustrated several simple and practical forms of my present improvements, and in which similar reference characters designate corresponding parts throughout the several views,—

Figure 1 is a longitudinal section through a sound producing device or voice showing one embodiment of the present invention;

Fig. 2 is a horizontal section taken substantially on the line 2—2 of Fig. 1;

Fig. 3 is a fragmentary view similar to Fig. 1 showing the weighty bellows head at an intermediate point of its collapsing movement;

Fig. 4 is an enlarged detail view of the magnetized guide post for the bellows head;

Fig. 5 is a sectional view taken on the line 5—5 of Fig. 4;

Fig. 6 is a fragmentary view similar to Fig. 1 showing an alternative embodiment of the device, and

Fig. 7 is a plan view of the valve member shown in Fig. 6.

In the drawings, for purposes of illustration, I have shown the mounting and arrangement of the several cooperative parts

of the device which is now well known in the art and consists essentially in an outer shell or casing 5 of cardboard tubing or other suitable material closed at its opposite ends by means of sheet metal heads 6 and 7 respectively. Within the casing 5 all of the operative parts of the device are enclosed. I have herein shown a familiar means for expelling air under pressure 10 through a suitable sounding reed comprising the usual tubular flexible bellows wall 8 having one of its end edges turned around one end edge of the casing wall 5 and fixedly clamped thereto by means of the metal cap 15 or head 6. The other end edge of this flexible bellows wall has an air tight connection with a gravity movable air expelling head 9. In the present instance, I have shown this air expelling head as consisting of an outer cup-shaped section 10 and an inner section 11 telescopically fitted within said outer section, said inner section having a short marginal flange 12 between which and the flange of the outer section 10, the end 25 edge of the flexible bellows wall is frictionally clamped. The intermediate body walls of the two head sections 10 and 11 are spaced apart to provide therebetween a sound receiving chamber 13. The wall of 30 the bellows head section 11 is provided with a suitable sounding reed indicated at 14 through which the air is expelled under pressure from the interior of the bellows and is emitted in the form of sound waves 35 into the chamber 13. The specific form of the bellows head as just described and the reed construction shown in the drawing are not herein claimed, since such subject matter is fully disclosed and claimed in a co-pending 40 application for patent filed by me on May 9, 1925, Serial No. 29,005, and it will become apparent as this description proceeds that in so far as the novel features of the present disclosure are concerned, the 45 sounding reed might be of any conventional construction and that various other means might be employed for the purpose of expelling air under pressure through such a reed.

50 In the embodiment of the device as illustrated in Fig. 1 of the drawings, I provide a central axially positioned guide post 15 for the weighty gravity movable bellows head, the two sections 10 and 11 of said head being centrally provided with suitable 55 openings therein snugly receiving the post 15 but permitting of the free sliding movement of said head along the post. Adjacent to this post, the wall of the head section 10 is provided with one or more sound emission 60 openings 16 through which the sound is emitted from chamber 13 into the end of the casing 5 exterior of the bellows and from which it finally passes through openings 17 provided in the cap or closure head 65 on the end of the casing 5. The opposite ends of the post 15 may be centrally mounted or secured upon the two casing heads 6 and 7 in any approved manner. Preferably, this post is in the form of a solid 70 steel rod and as clearly shown in Fig. 4, one end portion of this post is provided at longitudinally spaced points with magnetized areas designated 18 and 19 respectively, and having the north and south poles at 75 each magnetized area located at diametrically opposite points on the periphery of said post so that the magnetic flux passes transversely through the post between said poles. 80

Between the two sections 10 and 11 of the bellows head a valve disc 20 loosely surrounds said post, said valve disc being of such size or diameter as to overlie the emission opening or openings 16 when in its 85 closed position. This valve disc is in the form of a soft iron washer and is instantly responsive to the influence of the magnetized areas 18 and 19 of the guide post. Preferably, although not necessarily, I provide 90 the upper side of this washer opposed to the wall of the head section 10 at the inner portion thereof with a raised annular rib or boss indicated at 21 so that when the washer is in closed position there will be a slight 95 clearance between the face of the washer and the inner end of the emission opening or openings 16. However, if desired in lieu of this spacing rib 21 on the washer I may provide the wall of the head section 10 with 100 a small orifice as indicated in the form of the invention shown in Fig. 6 of the drawings. 105

In the operation of the voice device above described, assuming that the device has first been held in the proper position to cause the distention of the bellows under the gravity movement of the head 9 in one direction along the post 15 and that the device is then inverted to the position shown in Fig. 1, 110 it will be noted that the washer or valve disc 20 is opposed to the magnetized area 18 nearest the end of the post and that therefore, said washer being subject to the influence of the electromagnetic currents will 115 be sustained against a gravity movement on the post independently of the bellows head between the two sections 10 and 11 of said head so that the sound emission opening or 120 openings 16 are substantially closed. Thus, as the bellows head descends by gravity along the post the valve washer 20 is retained in this position relative to the emission openings, but since the bellows head is 125 sufficiently heavy to overcome the influence of the magnetic flux, said valve washer is moved over the magnetized area of the post by the head as it descends. During the initial descending movement of the bellows head, the sound created by the expulsion of 130

the air from the chamber through the reed 14 passes in restricted volume from the chamber 13 between the upper face of the washer plate and the wall of the head section 10, and hence through the emission openings 16 and finally through the openings 17 in the end head of the casing. This initial restricted emission of sound simulates the letter "m". As the bellows head in its continued descent, moves the valve disc or washer 20 below the magnetized area 18 of the post so that said washer is no longer subject to the influence of the electromagnetic currents, the valve washer drops by gravity independently of the bellows head along the guide post 15 to a position of rest upon the lower head section 11, thus fully opening communication between the chamber 13 and the emission openings 16 so that the sound may pass from said chamber in maximum volume through said emission openings and thereby simulate the pronunciation of the letter "a", thus completing the first syllable "ma". The sound of the letter "a" continues during the interval of movement of the bellows head between the two magnetized areas of the post as indicated in Fig. 3 of the drawings, and until the valve washer 20 is opposed to the north and south poles of the second magnetized area 19 of the post. Said washer is then held by the electromagnetic influence in a stationary position relative to the bellows head so that in the continued descent of the head the valve washer will again assume the closed position shown in Fig. 1 relative to the emission openings 16. Thus the letter "m" is again sounded until the valve washer is moved by the bellows head below the area of electromagnetic influence when it again drops by gravity independently of the head to the open position shown in Fig. 3 and during the remainder of the descent of the weighty bellows head the letter "a" will be sounded, thus completing the infant cry "ma-ma", which will thus be realistically simulated.

In so far as I am aware I believe that I am the first in the art to provide in a device of this kind a magnetically controlled valve means for effecting the articulation of the sound. It will be seen that in such a device, the necessity of producing special tools, more or less expensive dies, and difficult machining operations are obviated, and that the cost of production of such device will therefore, be correspondingly reduced. Nevertheless, it will be appreciated that a device of this construction will be positive and reliable in its operation so that notwithstanding rough usage or abuse of the article within which the device is incorporated, the proper articulation of the sound is assured. The guide post, the valve and parts of the weighty bellows head are all of substantial and rugged construction so that there is

practically no liability that due to distortion or displacement, they will fail to properly function at all times.

In Figs. 6 and 7 of the drawings, I have illustrated an alternative form of the device wherein instead of providing the valve member in the form of a soft iron washer or disc, this valve member 20' is in the form of a sheet metal stamping preferably of spring steel and includes a central disc provided with a plurality of radially disposed resilient arms 22. The extremities of these arms are adapted to bear against the inner surface of the section 10 of the bellows head when the valve is in its closed position. In this case, the valve disc 21 completely closes the sound emission openings 16, and therefore, the wall of the head section 10 is provided with a small diameter orifice 23 through which the sound may escape from chamber 13 in restricted volume to simulate the sound of the letter "m". In this construction, the central guide post for the movable bellows head is provided with the same spaced magnetized areas as above referred to. As shown in Fig. 6 of the drawings, the device has just been returned to an upright position after distending the bellows and the bellows head has moved downwardly slightly until the valve disc which is held stationary by the first magnetized area on the post is engaged by the inner face of the wall of the head section 10. The spring arms 22 are placed under a slight tension which however, is insufficient to cause a movement of the valve disc 21 on the magnetized area of the post with relation to the wall of the bellows head. The emission openings 16 are thus completely closed and during the first part of the descent of the bellows head while the valve disc is subject to the magnetic influence of the first magnetized area of the post, the sound is emitted in small volume through the orifice 23. Thereafter, the operation is substantially the same as that formerly described in connection with Fig. 1 of the drawings and the two word syllables "ma-ma" are successively sounded. It will be understood that the interval of time elapsing between the sounding of the two syllables may be increased or decreased by the proper spacing of the two magnetized areas 18 and 19 of the post, as may be desired.

From the foregoing description considered in connection with the accompanying drawing, the construction, manner of operation and several advantages of my present improvements will be clearly and fully understood. It will be seen that I have succeeded in devising a sound controlling or articulating means for such voice devices which is exceedingly simple in its construction, not liable to get out of order and highly efficient in the performance of its func-

tions. While I have herein disclosed several simple and practical embodiments of the device, it will nevertheless, be understood that the essential features of my present improvements might also be embodied in various other alternative structures, and I accordingly reserve the privilege of adopting all such legitimate changes as may be fairly embodied within the spirit and scope of the 10 invention as claimed.

I claim:

1. In a sound producing device for dolls and the like, an air chamber and a movable member constituting one end of said air 15 chamber having spaced walls providing a sound receiving chamber, a sounding reed in communication with said chamber operated by the passage of air in the movement of said member in one direction, one 20 of said walls having a sound emission opening, and valve means for said opening including a valve element within said sound receiving chamber unattached to the chamber walls and means co-acting with said 25 valve element in one operative movement of said member to cause an independent movement of said valve element and member, each with relation to the other in a direction parallel to the path of movement of 30 said member to control the passage of sound through said opening.

2. In a sound producing device for dolls and the like, an air chamber and a movable member constituting one end of said air 25 chamber having spaced walls providing a sound receiving chamber, a sounding reed in communication with said chambers operated by the passage of air in the movement of said member in one direction, one of said 40 walls having a sound emission opening, and valve means for said opening including a valve element within said sound receiving chamber and supported in a normal position upon one of said walls in spaced relation 45 to said opening to permit of the unimpeded passage of sound therethrough, and means for moving the valve element from such normal position and retaining the same in emission impeding relation to said opening 50 during a part of the movement of said member.

3. In a sound producing device for dolls and the like, an air chamber and a movable member constituting one end of said air 55 chamber having spaced walls providing a sound receiving chamber, a sounding reed in communication with said chambers operated by the passage of air in the movement of said member in one direction, one of said 60 walls having a sound emission opening, and valve means for said opening including a valve element within said sound receiving chamber movable in a direction parallel to the path of movement of said member, said 65 valve element being normally supported by

one of said walls in non-impeding relation to the emission opening to permit of the free passage of sound therethrough, and means repeatedly acting upon said valve element in the movement of said member in 70 one direction to cause said valve element at spaced intervals of such movement of said member to assume a position in close relationship to said opening and impede the passage of sound therethrough.

75

4. In a sound producing device for dolls and the like, a casing having an air chamber therein, a sounding reed and a weighty head reciprocating in said casing to expel air from said chamber through the reed, a post extending through said weighty head, said head having a sound emission opening in the wall thereof, a valve element slidingly mounted on the post and movable by gravity thereon independently of the weighty head to an open position with respect to the sound emission opening, and said post having longitudinally spaced means successively cooperating with the valve element to hold the same in a stationary position relative to the weighty head to thereby interrupt the passage of sound through said sound emission opening.

90

5. In a sound producing device for dolls and the like, a sounding reed, means for forcing air under pressure through said reed, a movable valve member for articulating the sound produced by said reed, and a guide for said valve provided with a magnet controlling the operation of the 100 valve.

105

6. In a sound producing device for dolls and the like, a sounding reed, means for forcing air under pressure through said reed, valve means for articulating the sound produced by said reed, and magnetic means controlling the operation of said valve means.

110

7. In a sound producing device for dolls and the like, an air chamber and a gravity movable weighty member for expelling air under pressure from said chamber, a sounding reed through which the air is expelled, a fixed post guiding said air expelling member, valve means carried by said weighty member and movable therewith along the post, and spaced magnetic means on said post controlling the operation of said valve means to articulate the emission of sound produced by said reed.

115

8. In a sound producing device for dolls and the like, an air chamber and a weighty gravity movable member for expelling air from said chamber under pressure, a sounding reed through which the air is expelled, a guide post for said member, said member having a sound emission opening, a valve associated with said opening surrounding the post and movable by gravity thereon independently of said member to an open posi- 120

125

130

tion, and longitudinally spaced means on said post successively cooperating with said valve in the air expelling movement of said member to retain the valve in a closed position for movement as a unit with the air expelling member and thereby articulate the emission of sound through said opening.

9. In a sound producing device for dolls and the like, an air chamber and a gravity movable member for expelling air from said chamber under pressure, a sounding reed through which the air is expelled, a guide post for said member, said member having a sound emission opening, a valve disc associated with said opening surrounding the post and movable by gravity thereon to an open position, said guide post having longitudinally spaced magnetized areas successively influencing the valve disc to hold the same stationary relative to the air expelling member and in a closed position with respect to the emission opening to thereby articulate the emission of sound through said opening.

25 10. In a sound producing device for dolls and the like, an air chamber and a gravity movable member for expelling air from said chamber under pressure, a sounding reed through which the air is expelled, a sound receiving chamber having a sound emission opening, a valve associated with said opening and movable relative to said opening to an open position, and means operative at spaced intervals in the air expelling movement of said member to magnetically hold the valve in a stationary position relative to the sound emission opening to thereby articulate the passage of sound through said opening.

40 11. In a sound producing device for dolls and the like, an air chamber, a gravity movable member for expelling air under pressure from said chamber, a sounding reed through which the air is expelled, said member having a sound receiving chamber, a fixed guide post for said member, one wall of said chamber having a sound emission opening therein, a valve disc surrounding said post and movable by gravity thereon independently of the air expelling member to an open position with respect to said sound emission opening, and said guide post having longitudinally spaced magnetized areas successively influencing said valve disc in the air expelling movement of said member to retain the disc in a closed position against gravity movement independently of said member and thereby articulate the emission of the sound through said opening.

60 12. In a sounding device for dolls and the like, an air chamber and a gravity movable weighty member for expelling air under pressure from said chamber, a sounding reed through which the air is expelled, valve means for articulating the sound produced

by said reed, a post disposed in parallel relation to the direction of movement of said weighty member, and spaced magnetic means on said post controlling the operation of said valve means.

70 13. In a sound producing device for dolls and the like, an air chamber and a gravity movable weighty member for expelling air under pressure from said chamber, a sounding reed through which the air is expelled, a post disposed in parallel relation to the direction of movement of said weighty member and with respect to which said member moves, valve means carried by said weighty member for articulating the sound produced by said reed, and said post having spaced magnetized areas controlling the operation of said valve means.

75 14. In a sound producing device for dolls and the like, an air chamber and a gravity movable weighty member for expelling air under pressure from said chamber, valve means for articulating the sound produced by said reed carried by said weighty member, and a post extending through said weighty member and provided with a magnetized area controlling the operation of said valve means.

80 15. In a sound producing device for dolls and the like, an air chamber and a weighty gravity movable member for expelling air under pressure from said chamber, a sounding reed through which the air is expelled, a post extending through said weighty member, valve means carried by said member for articulating the sound produced by said reed, and said post having longitudinally spaced magnetized areas controlling the operation of said valve means.

85 In testimony that I claim the foregoing as my invention, I have signed my name hereto.

90 LEO J. GRUBMAN.
